GOLF PUTTER HEAD

John F. Schneider, Portland, Oreg.

Application May 11, 1959, Serial No. 55,861

Term of patent 14 years

(Cl. D34—5)

I claim:

The ornamental design for a golf putter head, substantially as shown.
